CONCRETE BUILDING MATERIAL

Robert S. Cade, Canton, Ohio

Application September 5, 1936, Serial No. 99,567

5 Claims. (Cl. 72—16)

The invention relates to concrete buildings and more particularly to a novel building material in the form of slabs or sheets of reinforced concrete.

The object of the invention is to provide reinforced concrete slabs, sheets or blocks by means of which a building may be cheaply, quickly and easily constructed with spaced rows of slabs or sheets forming a hollow wall with an air space therein.

Another object is to provide such slabs or sheets of concrete reinforced with expanded metal lath or the like projecting beyond the edges of the slabs.

A further object is to form a building of such slabs or sheets, the projecting edge portions of the expanded metal of adjacent slabs overlapping and forming a reinforcement for the concrete joints which are formed between the slabs.

A further object is to provide relatively narrow spacing slabs or sheets adapted to be located transversely through the hollow wall and having projecting edge portions of expanded metal lath or the like extended into the joints between slabs of the inner and outer tiers of the wall.

Another object is to provide slabs of angular shape for forming corner portions of the walls of a building.

A further object is to provide slabs of T-shape which may be used either for reinforcing the hollow wall or for starting a partition wall.

A still further object is to provide a novel form of slab or block having an integral window frame formed thereon.

The above, together with other objects which will be apparent from the drawing or which may later be referred to, may be attained by constructing the invention in the manner illustrated in the accompanying drawing, in which

Figure 1 is a plan sectional view of a portion of a wall constructed in accordance with the invention;

Fig. 2, a vertical transverse sectional view through a portion of the wall of a building constructed in accordance with the invention;

Fig. 3, a fragmentary elevation of the improved window frame construction; and

Fig. 4, a fragmentary elevation of one of the improved slabs or sheets.

Similar numerals refer to similar parts throughout the drawing.

The slabs or sheets indicated generally at 10 may be formed of concrete or the like of a height substantially that of the ceiling and of a suitable width for convenient handling and are preferably about one inch thick.

Each slab has a sheet of expanded metal lath, heavy wire mesh or the like as indicated at 11 imbedded through its center and projecting outward beyond each side edge of the slab as indicated at 12.

For forming corners of a building or wall, the angular slabs 13 are provided and are constructed in the same manner as the flat slabs 10 having the expanded metal lath or wire mesh 11 imbedded therein and projecting beyond the side edges thereof.

In constructing a building, a footer or sill 14 of cement or the like is formed and the wall is constructed by imbedding spaced walls of the slabs therein as indicated at 15. The adjacent side edges of the slabs are spaced apart sufficiently to permit the projecting edges 12 of the metal lath or wire mesh to overlap as shown in Fig. 1 and these joints are then filled with cement or the like to provide a continuous unbroken wall. 20 Wooden spacing strips 16 may be provided between the inner and outer tiers of the wall at the joints and may either remain in the wall or may be removed after the joints of the slabs have been cemented.

If desired, narrow slabs 10a, formed in the same manner as the slabs 10, may be provided at the joints, the projecting edges of the metal lath or wire mesh thereof extending into the joints so as to form a rigid structure when the 30 joints are filled with cement, the narrow transversely disposed slabs 10 thus reinforcing the hollow wall at intervals.

For the purpose of further strengthening the wall, T-shaped blocks or slabs 17 may be provided at intervals, these slabs being formed in the same manner as the slabs 10 and provided with a central rib 18 of a width substantially the distance between the inner and outer slabs of the hollow wall. This rib 18 is provided with a 40 reinforcing sheet of metal lath or wire mesh 19, the projecting edge of which extends into the joint between the slabs 10 so as to form a solid rigid structure when this joint is filled with cement.

In order to obviate the necessity of using wood or metal window or door frames, reinforced concrete units 20 may be provided around each window or door opening, having the integral ribs 21 formed thereon, producing an integral concrete window or door frame. These units, as shown in Fig. 1, may be of channel-shape and provided with expanded metal lath or wire mesh reinforcing sheets 22 of similar shape imbedded therein, the edges of said reinforcing sheets pro- 50 55

jecting beyond the edges of the unit so as to overlap the projecting edges 12 from the slabs 10, whereby a reinforced concrete joint may be formed between the units 20 and the slabs. Inside and outside trims may be moulded on said units 20.

In Fig. 3 is shown the manner in which a casement window sash 23 may be mounted within the window frame thus formed. Hinge leaves 24 10 may be fixed upon the sash in usual and ordinary manner and provided with elongated hinge pins 25 adapted to be received within the bushings 26 of lead or the like moulded within pre-formed sockets 27 in the upper and low units 20, or in 15 such sockets themselves the sash being adapted to swing into closed position against the ribs 21 upon the units 20.

A concrete cap 28 is placed upon the upper edges 20 of the slabs forming the wall for each story of the building and preferably has the depending rib 29 forming a spacer between the upper ends of the slabs 10 of the inner and outer walls. The floor joists 30, or at the top of the building beams for the roof, may have their ends imbedded in 25 the cap 28. This cap may have a groove 31 near its outer edge to receive the lower ends of the slabs 10 forming the outer wall of the next upper story, these slabs being preferably slightly higher than the slabs 10 for the inner wall of said upper 30 story.

For the purpose of properly spacing the inner and outer slabs 10 of said upper story, a wooden plank or strip 32 may be mounted upon the floor joists 30 acting as a stop against which the slabs 35 forming the inner wall may be butted.

The slabs may have smooth surfaces for both the inner and outer walls, which permits of their being painted, plastered, stuccoed or otherwise finished, or any desired finish such as a pebble 40 dash, Spanish or antique plaster or the like may be moulded in the surfaces of the slabs so as to produce the desired finish without additional cost.

As shown in Fig. 3, the channel-shaped window 45 and door frames may be reinforced at their corners by an integral diagonal rib 33 of concrete moulded in the frame and extending transversely across the inside of the channel.

Holes may be formed in the top corners and 50 sides of the reinforced concrete window units to receive wooden plugs or pins 34 and 35 respectively to provide for easily attaching curtain rods, shade rollers and tiebacks for curtains or drapes.

It will be obvious that with the construction 55 above described, a very strong integral wall is produced since the joints between slabs or units are formed of the same concrete material as the slabs or units themselves, thus producing a cohesion of the various slabs, units and window and door frames rather than an adhesion such as where tiles, blocks, bricks or the like of clay or similar material are joined together by mortar or the like.

A building so constructed will be greatly reduced in weight and greatly increased in strength over the ordinary brick or frame building because of the ideal method of distribution of reinforcing material and concrete throughout the walls of the building.

70 I claim:

1. A hollow wall including two spaced rows of concrete slabs each having reinforcing mesh sheets imbedded therein and projecting beyond the op-

posite side edges thereof, the projecting portions of the mesh sheets on adjacent slabs being overlapped and not connected to each other, transversely disposed, similarly constructed slabs located through the wall at the joints between the 5 first named slabs and having mesh sheets imbedded therein with their projecting portions extended into said joints, and not connected to the first named projecting edges, the joints being filled with concrete to form keys by extending 10 through said mesh projections forming a solid, continuous reinforced, concrete wall.

2. A hollow wall including two spaced rows of concrete slabs each having reinforcing mesh sheets imbedded therein and projecting beyond the opposite side edges thereof, the projecting portions of the mesh sheets on adjacent slabs being overlapped and not connected to each other, certain of said slabs being T-shaped and having angular 15 ribs located through the wall at the joints between the first named slabs and having mesh sheets imbedded therein with their projecting portions extended into said joints, and not connected to the first named projecting edges, the joints being filled with concrete to form keys by 20 extending through said mesh projections forming a solid, continuous reinforced, concrete wall.

3. A hollow wall including two spaced rows of concrete slabs each having reinforcing mesh sheets imbedded therein and projecting beyond the opposite side edges thereof, the projecting portions of the mesh sheets on adjacent slabs being overlapped and not connected to each other, transversely disposed, similarly constructed slabs located through the wall at the joints between the 35 first named slabs and having mesh sheets imbedded therein with their projecting portions extended into said joints, and not connected to the first named projecting edges, the joints being filled with concrete to form keys by 40 extending through said mesh projections forming a solid, continuous reinforced, concrete wall, certain of the slabs being angular to form corners in the wall.

4. A hollow wall including two spaced rows of 45 concrete slabs each having reinforcing mesh sheets imbedded therein and projecting beyond the opposite side edges thereof, the projecting portions of the mesh sheets on adjacent slabs being overlapped and not connected to each other, certain 50 of said slabs being T-shaped and having angular ribs located through the wall at the joints between the first named slabs and having mesh sheets imbedded therein with their projecting portions extended into said joints, and not connected to the 55 first named projecting edges, the joints being filled with concrete to form keys by extending through said mesh projections forming a solid, continuous reinforced, concrete wall, certain of the slabs being angular to form corners in the wall.

5. A hollow wall including a row of concrete slabs, each having reinforcing mesh sheets imbedded therein and projecting beyond opposite side edges thereof, the projecting portions of mesh 65 sheets on adjacent slabs being overlapped and not connected to each other, the joints between adjacent slabs being filled with concrete to form keys by extending through said mesh projections forming a solid, continuous, reinforced concrete 70 wall.

ROBERT S. CADE.
